(57) **CLAIM**

The ornamental design for a nose cover for eyewear or the like as shown and described.

DESCRIPTION

FIG. 1 is a perspective view of nose cover for eyewear or the like showing my new design;

FIG. 2 is a front elevation view thereof;

FIG. 3 is a rear elevation view thereof;

FIG. 4 is a right side elevation view thereof, the left side being a mirror image thereof;

FIG. 5 is a right side elevation cross-section view thereof taken along line 5-5 in FIG. 2;

FIG. 6 is a top plan view thereof;

FIG. 7 is a bottom plan view thereof; and,

FIG. 8 is another perspective view thereof, shown in the environment of eyewear.

The broken lines illustrate features of the nose cover for eyewear or the like that form no part of the claimed design.
